UNITED STATES PATENT OFFICE.

NICHOLAS J. CONRAD, OF, CHICAGO, ILLINOIS, ASSIGNOR TO SCHWEITZER & CONRAD, INC., OF CHICAGO, ILLINOIS, A CORPORATION OF ILLINOIS.

Mounting for Circuit-breakers.

1,245,151.

Specification of Letters Patent.

Patented Nov. 6, 1917.

Application filed February 2, 1917. Serial No. 146,244.

To all whom it may concern:

Be it known that I, NICHOLAS J. CONRAD, a citizen of the United States, residing at Chicago, in the county of Cook and State of Illinois, have invented a certain new and useful Improvement in Mountings for Circuit-breakers, of which the following is a full, clear, concise, and exact description, reference being had to the accompanying drawings, forming a part of this specification.

My invention relates to mountings for circuit breakers, particularly for high tension fuses and switches.

The object of the present invention is to provide an improved form of mounting which is compact, requires little room for mounting, may be constructed at low cost and which affords ample electrical protection.

20 The embodiment which I have illustrated in the accompanying drawings is adapted for either indoor or outdoor installation. I have illustrated the same as adapted to mount a fuse of the type shown in the patent 25 to Schweitzer and Conrad No. 1,135,548 granted April 13th, 1915, but it is to be understood that the fuse to be mounted may be of any type desired. It is further to be understood that a switch blade may be 30 mounted in place of the fuse shown in the drawings.

Mountings of this type as heretofore constructed have been provided with a pair of insulating supports mounted in a generally 35 parallel relation upon a base which has been made of a length equal to or greater than the length of the fuse or switch. As a consequence it has heretofore been found necessary to provide a supporting frame of considerable extent either for the mounting 40 itself or for the base of the mounting. This is not only expensive but also generally inconvenient and in some cases impossible.

My invention aims to dispense with the 45 necessity for such extensive support and provides a pedestal of such dimensions as to be readily mounted directly upon a wall or upon any suitable support even though the same be of small extent. A pair of divergent 50 arms of insulation are secured to the base and at their outer ends support the ends of the circuit breaker.

In the accompanying drawings—

Figure 1 is a side elevation of one form 55 of mounting;

Fig. 2 is an end elevation of the same; and Fig. 3 is a side elevation of a modified form of mounting.

The mounting comprises a pedestal 1 having a generally rectangular base 2 of such dimensions as to be readily mounted upon a wall, a frame or upon the side of a cross arm 3 as is shown in Fig. 3. The base 2 is provided with bolt holes 4 through which suitable bolts may be passed to secure the pedestal in any desired position. The preferred position of the mounting is such as to hold the fuse 5 in a generally vertical position. Hence the length of the base portion 2 in a vertical dimension, as shown in Fig. 1, is 60 made substantially equal to or less than the width of a cross arm 3 upon which it may be mounted in the case of an outdoor installation.

It is to be understood that the mounting 75 may be placed on any other support desired, such for instance as a frame made of pipe or the like. In such event the base of the pedestal is made of suitable configuration to be attached to the pipe.

The pedestal 1 is provided with a pair of sockets 6 and 7 into which are fastened the ends of the posts or columns 8 and 9 of insulation. These columns 8 and 9 in the embodiment of Figs. 1 and 2 are made of 85 tubes of insulation preferably of a relatively strong material such as fiber impregnated with bakelite. The lower ends of the columns are secured in the tubular sockets 6 and 7 by means of pins 10 and 11.

Metal caps 12 and 13 which are provided with tubular sockets 14 and 15 are mounted on the outer or divergent ends of the columns 8 and 9. These socket members 14 and 15 are secured to the columns by means 90 of pins 16 and 17. The caps 11—12 may be secured to the upper ends of the columns in a number of different ways as is well understood by those skilled in the art, the 95 sockets and pins being but one of many ways for securing this result. The cap members 12 and 13 are preferably provided with inwardly extending lips 18 and 19 which provide supports for the spring clips 20 and 21 that embrace the metallic terminals 22 and 23 of the fuse 5. The spring clip 21 is provided with a stop or support 24 for insuring the correct position of the fuse 5 in the spring clips 20 and 21 and for supporting the lower end of the same to prevent 105 110

axial displacement. Suitable line terminals 26 and 27 are connected to the metal caps 12 and 13 by means of bolts 28 and 29.

The fuse 5 which I have shown is of the type employing a bath of arc extinguishing liquid and movable fuse terminals which are adapted to be separated by spring tension upon destruction of the fuse.

The top of the fuse is provided with a removable venting member 30 which is adapted to release the pressure generated upon violent blowing of a fuse.

Where the mounting supports a switch, the blade is pivoted at one end upon one cap member such as 12 and a corresponding contact for the blade is mounted upon the other 13. I have not illustrated the same as the particular form of a switch or circuit breaker employed is immaterial.

In the embodiment of Fig. 3 I employ columns 32 and 33 of molded insulation with surface corrugations for increasing the creepage distance across the surface of the insulating material. Due to the diverging arrangement of the columns 32 and 33, the corrugations 34 and 35 are substantially at right angles to each other and at substantially 45 degrees to the vertical.

The mounting is generally set either in the vertical position or in the horizontal position. In either case the corrugations 35 lie at 45 degrees to the vertical and thus drain off such moisture or precipitation as may fall upon them equally well in either position.

The columns 32 and 33 are preferably made of molded insulation and may be of any configuration desired. I have shown the same as of a gradually increasing and decreasing diameter throughout the corrugations.

In the form shown in Fig. 3, the spring clips 20 and 21 which engage the terminals of the fuse 5' are mounted upon metallic extensions 36 and 37 which connect the spring clips with the line terminals 26 and 27. It is to be noted that one size of mounting may be employed for different sizes of fuses by providing the proper lengths of connecting plates 36 or 37 the mounting device being to that extent adjustable for mounting different sizes of fuses.

The fuse 5 illustrated in Figs. 1 and 2 is provided with a shell or casing constructed of glass tubing. The fuse 5' shown in Fig. 3 has a shell or casing of bakelite or of fiber impregnated with bakelite. Except as to the features above mentioned the embodiment of Fig. 3 is the same as shown in Figs. 1 and 2. It is understood that the fuse 5' is illustrative of any suitable circuit breaker.

The columns of insulation which I have shown preferably extend at an angle to each other of about 90°. This angle may be varied and it is to be understood that the col-

umns need not be straight as it is obvious that the advantages of my invention may be secured without a strict adherence to the showing of the drawings. I do not intend to be limited to the precise details shown and described.

I claim:

1. In combination, a generally rectangular metal pedestal, said pedestal having tubular sockets with axes lying in substantially the same plane and substantially at right angles to each other, columns of insulation having their ends resting in said sockets, means for securing said columns in said sockets, caps for said columns, said caps having tubular sockets adapted to fit over the ends of said columns and having substantially flat top surfaces parallel to the base of said pedestal, means for holding said caps upon the ends of said columns, and connecting clips mounted upon said caps, said clips being adapted to support a connecting member substantially parallel to the plane of the base.

2. In combination a metal pedestal, said pedestal having two sockets with their axes in the same plane and extending substantially at forty-five degrees to the plane of the base, columns of insulation having their ends resting in said sockets, said columns having corrugated sides to increase the creepage distance, said corrugations on the columns extending substantially at forty-five degrees to the vertical whereby the nature of the creepage path is unaffected by change in position, and terminal supports mounted on the ends of said columns.

3. In combination, a pedestal having relatively small base, said base having two sockets thereupon, the axes of these sockets being inclined at an angle to the base of the pedestal, said axes lying in substantially the same plane, columns of insulating material mounted in said sockets, metallic caps mounted on said columns, said caps having their top surfaces substantially parallel to the plane of the base, terminal members for a line secured to said caps and connecting clips supported by said caps in electrical connection with said terminal members.

4. In combination, a pedestal having a small base, a pair of columns extending at substantially right angles to each other and mounted on said pedestal, said columns lying in substantially the same plane, caps for said columns, said caps having their tops substantially parallel to the base of the pedestal, a connecting plate mounted on one of said caps, a terminal connected to said plate and a connecting clip for embracing a connecting member mounted on said plate.

5. In combination, a metallic pedestal having a small base, a pair of columns of insulation secured to said base at an angle to each other, metallic caps for said columns

- and supporting terminals for a connecting member mounted on said caps.
6. In combination, a pedestal having a base of small width and length, a pair of 5 columns of insulation secured to said base to support the ends of a circuit breaker, said columns having their outer ends divergent, metallic caps on said columns and supporting terminals for a circuit breaker on said 10 caps.
7. In combination a pedestal having a relatively small base, a pair of columns extending at substantially right angles to each other and at substantially forty-five degrees 15 to the vertical, said columns being mounted on said pedestal and lying in substantially the same plane, caps mounted on said columns in insulating relation to said base and to each other, said caps being of substantially equal distance from the base, terminal 20 members for said caps and means for supporting a circuit breaker upon said caps.
8. In combination, a pedestal having a small base, a pair of columns of insulation
- secured to said base, said columns diverging 25 from each other, caps for said columns and a circuit breaking member connected between said caps, said base being of substantially less extent than the distance between said caps.
9. In combination, a relatively small pedestal having a pair of tubular sockets extending therefrom at substantially 90° to each other, insulating members situated in said sockets, caps for the ends of the columns, said caps having sockets fitting the ends of the insulating members, said caps having flat tops extending in substantially the same plane toward each other, a spring 35 clip on each cap, a supporting finger lying 40 outside one of said clips, said clips being adapted to be connected by a fuse, and a terminal clip electrically connected to the cap.

In witness whereof I hereunto subscribe 45
my name this 31st day of January, A. D.
1917.

NICHOLAS J. CONRAD.
